UNITED STATES PATENT OFFICE.

JOHN G. S. HALL, OF CHICAGO, ILLINOIS.

WEATHER STRIP.

Application filed December 2, 1925. Serial No. 72,714.

My present invention relates to improvements in weather strips and has for its principal object the provision of a device of this character that is flexible throughout its entire length whereby the same may be caused to fit into the corners formed by the longitudinal and transverse members of doors and window frames, and similar openings and at the same time provide an air-tight and water-tight joint between the frame and the movable member. With a device of this character the person installing the same may use a continuous length of my improved weather strip for each opening thereby avoiding the necessity of having to cut and miter the same to fit it into each corner. This affords a considerable saving in material and labor, and time consumed in each installation. I prefer to fabricate the weather strip entirely of rubber thus materially reducing the cost of production for the reason that the same may be made in any desired continuous length upon a machine in which the rubber is forced through suitably shaped molds in the nozzle of the apparatus, and as the structure is made entirely of one material it requires little or no handling after leaving the machine excepting the usual vulcanizing step which retains the article in the desired shape.

In designing my improved weather strip I have provided a cylindrical or bead member that is connected to the attaching body or fin by a reduced portion or neck so as to facilitate the compression or distortion of the cylindrical or bead member when in use to cause the strip to fit snugly into the corner it is desired to protect. The whole structure is formed in a curve with the cylindrical or bead member forming the outer circumferential edge so that when the strip is being installed it will present a convex edge to the movable element mounted in the door or window-frame or other opening.

I prefer to carry out my invention and to accomplish the several objects thereof in substantially the manner hereinafter fully described and as more particularly pointed out in the claims, reference being here made to the accompanying drawings that form a part of this specification.

In the drawings:—

Figure 1 is a perspective view of an end portion of my improved weather strip.

Figure 2 is a transverse sectional view of a frame surrounding an opening and the

closure therefor, with my weather strip in transverse section thereon.

Figure 3 is an enlarged sectional view of my weather strip, illustrating a preferred embodiment thereof.

Figure 4 is a similar view of a slightly modified construction thereof.

The drawings are in a sense merely schematic and to illustrate a typical or preferred embodiment of my invention, and in these drawings similar reference characters have been employed to designate like parts wherever the same appear throughout the several views.

By referring to these drawings it will be seen my invention preferably comprises a cylindrical or bead member 5 that forms the outer edge or engaging and sealing portion of the weather strip, and the same may be either hollow or solid as illustrated and for the purpose of both convenience and utility I prefer to make the bead member of round section. The member by which the weather strip is attached to the door or window-frame or the like consists of a holding piece in the form of a fin 6 that is preferably of wedge or V-shape with the sides converging away from the bead member so that the apex thereof is farther away from the bead member and the base of the wedge is adjacent thereto. This fin, as will be noted from the drawings, is substantially radially disposed with respect to the bead member and either of its sides is adapted to be placed flat against the frame 7 or other support to which the structure is to be secured and the edge of the bead member will be in a position to be engaged by the movable door or window 8 when the latter is moved against the weather strip, which action causes a slight compression or distortion of the bead member. In order to readily accommodate this compression or distortion of the bead member, and thereby to insure a tight, snug fit in the corners of the structure in which the weather strip is mounted I prefer to connect the bead member 5 to the fin 6 by a reduced portion 9 in the form of a short narrow neck or web 10 which permits a greater flexibility of the portion of the weather strip that extends beyond the attaching fin 6. The base 11 of the fin may be straight, as shown in Figs. 1, 2, and 3 of the drawings, or the same may be curved and concaved as illustrated in Fig. 4 of the drawings, and the connecting

105
110

or reduced portion may be either long or short as shown respectively in Figs. 3 and 4. When the weather strip has been attached by inserting tacks through the fin portion 5 and into the door or window-frame it will be seen the fin 6 lies flat against the supporting surface with its pointed edge or apex farthest away from the door or window or other closure member, and because of its 10 tapered or wedge-shaped formation this edge offers no obstruction which might tend to tear the same away and at the same time gives the appearance of merging into the support. The closing of the door or window 15 will cause a compression or distortion of the cylindrical or bead member somewhat in the manner shown in Fig. 2 of the drawings, which will form a water-tight and air-tight joint at the location desired.

20 The weather-strip I have herein disclosed is formed entirely from rubber or other flexible or elastic material so that it may be flexed or bent, or pulled in any direction and thereby made to conform to the shape 25 or design of the structure to which it may be secured. As before stated it is made in continuous lengths so there is no waste, and when the same is being installed one end of the strip is secured to the window or door- 30 frame at one corner thereof, preferably at the lower corner of a door, and the same tacked up one side, then across the lintel and then down the other side to the sill where it is severed at the proper place, and 35 thus all joints are avoided.

What I claim as new is:—

1. An integral weather-strip structure of resilient material comprising a longitudinal bead and a holding-strip, said holding-strip 40 having its major transverse axis radial to the bead.
2. An integral weather-strip structure of resilient material comprising a longitudinal bead and a holding-strip, said holding-strip 45 having its major transverse axis radial to the bead and connected to the bead by a reduced integral portion.
3. A weather-strip comprising a longitudinal holding-piece, a longitudinal bead 50 spaced from an edge thereof, and a neck connecting said holding-piece and bead, all of said parts formed of flexible material and normally shaped in a longitudinal arc.

4. A weather-strip comprising a holding-piece having an integral bead upon an edge 55 that is connected thereto by a reduced portion, said structure formed entirely of rubber and normally curved in the direction of its length.

5. A weather-strip comprising a longitudinal holding piece of substantially V-shape section, a longitudinal bead spaced from the edge of the holding piece opposite the apex thereof, and means connecting said holding piece and said bead. 60

6. A weather-strip comprising a longitudinal bead, and a longitudinal holding piece integral therewith, said holding piece being formed substantially V-shape in section and disposed with the base of the same adjacent 70 to the bead and connected thereto by a reduced portion of the material.

7. A weather-strip comprising a longitudinal holding piece of substantially triangular section, a short neck extending from the base thereof, and a member on the outer edge of said neck and having sides that extend laterally from the neck, all of said parts formed from an integral piece of yieldable material. 75

8. A weather-strip comprising a longitudinal holding-piece, and an integral bead upon an edge thereof, said parts formed of flexible material and normally shaped in an elongated arc. 80

9. A weather strip comprising a longitudinal holding-piece having an integral bead upon the edge and formed entirely of rubber, said strip being normally curved in the direction of its length. 90

10. A weather-strip comprising a longitudinal bead and a longitudinal holding piece extending radially therefrom, said holding piece being of tapered cross-section and formed integrally with said bead. 95

11. A weather-strip comprising a longitudinal bead, and a longitudinal holding piece extending radially therefrom and formed integrally therewith, the sides of said holding-piece converging away from the bead. 100

Signed at Chicago, in the county of Cook, and State of Illinois, this 20th day of June, 1925.

JOHN G. S. HALL.
